UNITED STATES PATENT OFFICE.

CARL G. ALLGRUNN, OF MIDDLEPORT, NEW YORK, ASSIGNOR TO NIAGARA SPRAYER CO., OF MIDDLEPORT, NEW YORK, A CORPORATION OF NEW YORK.

DUST GUN.

Application filed March 10, 1924. Serial No. 698,260.

The present invention relates to new and useful improvements in dusting devices, and it pertains more particularly to devices of this character especially adapted for distributing insecticide or the like on growing crops.

It is one of the primary objects of the present invention to provide a relatively small manually operated portable device for 10 distributing insecticide.

It is a further object of the invention to provide a device of this character in which the insecticide in the form of powder is precipitated by means of an air blast.

15 It is a further object of the invention to combine with the device means for placing the air under pressure which means is double acting, thus insuring a constant supply of air under pressure.

20 With the above and other objects in view, reference is had to the accompanying drawings, in which—

Figure 1 is a plan view partly in section, of a device constructed in accordance with 25 the present invention;

Fig. 2 is a view in side elevation of the improved device;

Fig. 3 is a detail sectional view taken on the line 3—3 of Fig. 1;

30 Fig. 4 is a detail view, partly in elevation and partly in section, of a discharge nozzle used in combination with the device, and

Fig. 5 is a similar view taken at right angles to Fig. 4.

35 Referring more particularly to the drawings, the device comprises a housing 10. This housing is formed with a rectangular portion 11 and a circular portion 12, and interposed between the rectangular portion 11 and the circular portion 12, there is a curved partition 13. This curved partition 13 divides the housing into a pump cylinder 14 and a dust or powder chamber 15. Leading 40 from the dust or powder chamber 15, there is a discharge pipe 16, and positioned over the inner end of the discharge pipe 16 there is a screen or the like, 17, which serves to prevent particles or lumps of dust from being discharged through the pipe 16. Carried by the side wall of the pump cylinder 14, there is a stuffing box 18, and mounted in said stuffing box 18 there is a piston rod 19, upon the inner end of which is secured a piston 20. A spring 21 surrounds the piston rod 19 and serves to aid in starting the 50

piston on its inward stroke and to relieve the shock at the end of its outward stroke. This piston 19 is connected by means of a link connection 22 to a lever 23. The lever 23 has a handle 24 on one end and at its other end it is pivotally connected, as at 25, to a bracket 26 rigidly secured as at 27 to the wall of that part of the housing which forms the dust chamber 15. The reference character 28 designates a small housing, and 60 mounted therein there is a flap valve 29 which controls an opening 30 leading from the interior of the pump cylinder 14 to the housing 28. The side walls of the housing 10 are each provided with an opening 31, 70 and leading from each opening 31 into the dust chamber 15, there is a pipe which constitutes a discharge nozzle 32.

It will be noted that the construction just described is duplicated on opposite sides of the housing 10, there being two housings 28, two openings 30, and two valves 29. The pump cylinder 14 is also provided at each end with openings 33 controlled by flap valves 34, and this construction provides the 80 air intake for the opposite ends of the pump cylinder 14.

On the side of the housing 10 opposite to that which carries the pivoted lever 23, a handle 40 is provided, and such handle is 85 spaced with respect to the housing 10 and carried by brackets 41.

One of the side walls of the powder or dust chamber 15 is provided with an opening adapted to be closed by a screw-threaded 90 cover 42, and such cover is provided with a handle 43 by means of which it is screwed into position to close the opening. This construction provides means for introducing insecticide in powder form into the dust 95 or powder chamber 15.

In Figs. 4 and 5 is shown a nozzle for use in connection with the device, and such nozzle comprises a tubular member 45, the end 46 of which is adapted to be received upon 100 the discharge pipe 16. The other end has a spreader 47 removably secured thereto, as at 48, such spreader comprising a member substantially U-shaped in cross-sectional form as shown.

105 The device operates in the following manner:

A sufficient quantity of insecticide in powder form having been introduced into the chamber 15, the cover 42 is screwed thereon 110

in order to render such chamber airtight. The handle 40 is now grasped in one hand and the handle 24 of the pivoted lever 23 is grasped in the other hand. Through the medium of the lever 23 the piston 20 is reciprocated in the cylinder 40, and air is alternately drawn through the intake valves 33 and discharged through the valves 30, and by means of the discharge nozzles 32 is introduced into the chamber 15 under pressure. As the air is introduced into the chamber it becomes laden with the insecticide contained therein, and as the air passes out it forms a vehicle for such insecticide which is projected through the discharge pipe 16 and the nozzle 45.

From the foregoing it is apparent that the present invention provides a new and efficient hand-operated device for dusting growing crops, and that the device is of such a construction as to render it readily portable and capable of directing a blast of material discharged therefrom.

What is claimed is:

1. In a device of the character described, a housing, a partition dividing said housing into a pump cylinder and an insecticide compartment, a pump mounted in the pump cylinder, means for operating said pump, and means for establishing communication between the pump cylinder and the insecticide compartment, said means comprising auxiliary housings formed on opposite sides of the first-mentioned housing, a valve establishing communication between each end of the pump cylinder and its respective auxiliary housing, and a discharge nozzle leading from each of said auxiliary housings into the insecticide compartment, said dis-

charge nozzles being angularly disposed 40 with respect to each other.

2. In a portable hand duster, a main housing having two adjacent openings in each of two oppositely disposed side walls, an auxiliary housing on the exterior of each of said side walls and enclosing its respective aforementioned openings, a controlling valve for one opening of each pair of said aforementioned openings, a partition extending transversely of the main housing and dividing the same into a pump chamber and an insecticide compartment, a pump mounted in said pump chamber and adapted to discharge air alternately through the aforementioned valve-controlled openings, and a nozzle projecting from each of the other openings into the insecticide compartment.

3. In a portable dust gun, a housing having a powder chamber and a pump chamber, a discharge nozzle at one end of said powder chamber, said nozzle extending substantially at right angles to the axis of said pump chamber, air conducting means connecting said pump chamber with said powder chamber, a piston reciprocable in said pump chamber, a piston stem protruding from one end of said pump chamber, a supporting arm extending laterally of the same side of the housing as said piston stem, a lever pivotally attached at one end to said supporting arm and having a handle at its opposite end, a link connecting said lever with the outer end portion of said piston stem, and a second handle supported on said housing at the side of the latter opposite to said lever.

CARL G. ALLGRUNN.
